UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

HANDLE CONSTRUCTION FOR BRACES AND THE LIKE.

Application filed April 18, 1921. Serial No. 462,386.

To all whom it may concern:

Be it known that I, WALTER I. TUTTLE, a citizen of the United States, and a resident of Providence, in the county of Providence and State of Rhode Island, have invented an Improvement in Handle Constructions for Braces and the like, of which the following is a specification.

This invention relates to the construction of handles and more particularly, handles for braces and the like. One of the objects thereof is to provide a device of the above nature, simple and practical in construction and efficient in action. Other objects are to provide a construction of the above nature which can be readily and cheaply manufactured, which will be light and durable and which will be characterized by an economical use of metal and avoidance of weakening of the co-acting parts. Other objects will be in part obvious and in part pointed out hereinafter.

The invention accordingly consists in the features of construction, combinations of elements and arrangement of parts which will be exemplified in the structure herein-after described and the scope of the application of which will be indicated in the following claims.

30 In the accompanying drawings in which is shown one of various possible embodiments of this invention,

Figure 1 is a sectional elevation thereof;

Figure 2 is a cross section taken substantially on the line 2—2 of Figure 1;

Figure 3 is an end view of a handle device;

Figure 4 is an end view of one of the component members thereof; and

40 Figure 5 is a sectional view along the line 5—5 of Figure 3.

Similar reference characters refer to similar parts throughout the several views of the drawings.

45 Referring now to Figure 1 of the drawings, there is shown at 10 the central or crank portion of a brace, the crank members 11 and 12 running respectively to the end thrust handle and to the device rotated by the brace such as a socket wrench, neither of which is shown herein as they form in themselves no part of the present invention.

Mounted upon the straight portion 13 of this member is a handle device which comprises a pair of identical steel stampings 14, an end view of one of which is shown in Figure 4. These steel stampings are semi-circular in general contour and complement each other in forming a handle of a general tubular construction. Each of the handle members is outwardly rounded as at 15 throughout substantially its entire length and at each end is flanged outwardly as shown at 16, the outward inclination of this flange with respect to the axis of the member 13 being preferably in the neighborhood of seven degrees.

At each end of the handle member thus formed there is provided a collar 17, best shown in Figures 3 and 5 of the drawings. This collar has a central opening 18 adapted to fit and yet turn freely upon the member 13. Each of these members moreover is provided with an annular recess 19 having in its original form an inner wall 20 tapered to fit the outward inclination of the flange 16. The outer wall 21 of this recess is normally cylindrical.

In assembling the parts the members 17 are inserted over one end of the brace and moved down substantially into the position shown in Figure 1 of the drawings and having their annular grooves 19 facing each other. In order to prevent movement of these members toward each other, there are provided a pair of sleeve pins 22 fixed in the member 13 and substantially engaging the inner edges of the collars as shown in Figure 1 of the drawings.

The pair of members 14 are then assembled to form a tubular handle and their flanges 16 are inserted within the recesses 19 of the adjacent collars 17. With the parts in these positions the outer wall of the recesses 19 is forced inwardly in such manner that it grips tightly the outer surface of the flanges 16 of the handle. The pressure by which this is achieved is carried to such an extent that the parts are substantially inseparable.

In this manner the handle member is not only light and rigid but extremely strong, and turns freely upon the portion 13 of the crank of the brace. Furthermore without any substantial weakening of this crank

member, the handle is held against longitudinal movement by the pins 22. The outward inclination of the flange 16 interlocks with the rigid walls of the collar 17, thus precluding the chance of endwise separation of the collars; and it will be seen that so long as the collars are in position a lateral separation of the members 14 is prevented. It will also be seen that as there is a simple smooth cylindrical bearing between this handle and the member 13, the friction in turning is reduced to a minimum.

As various possible embodiments might be made in the above invention and as various changes might be made in the embodiment above set forth, it is to be understood that all matter herein set forth or shown in the accompanying drawings is to be interpreted as illustrative and not in a limiting sense.

I claim as my invention:

1. In handle construction for braces and the like, in combination with the crank portion of the brace, a hollow member, a pair of collars respectively interlocking with the end edges of said hollow member and rotatably mounted on said crank portion, and projecting members positioned on said crank within said hollow member adapted to engage said collars and prevent longitudinal movement of the device along said crank portion.

2. In handle construction for braces and the like, in combination, a hollow member, and a pair of collars each journaled upon the brace and each having a groove facing toward the other, the walls of which enclose a recess shaped to conform to the shape of the adjacent end of said hollow member into which the adjacent end of said hollow member is fitted, the sides of said recess being pressed into gripping engagement with said end.

3. In handle construction for braces and the like, in combination, a hollow member, and a pair of collars each journaled upon the brace and each having a groove facing toward the other, the walls of which enclose a recess shaped to conform to the shape of the adjacent end of said hollow member into which the adjacent end of said hollow member is fitted, the sides of said recess being pressed into gripping engagement with said end, said hollow member being built up of a plurality of longitudinal sections.

4. In handle construction for braces and the like, in combination, a hollow member having its ends inclined outwardly with respect to its axis, and a pair of end members having similarly inclined annular recesses formed therein in which said ends are fitted

and between the walls of which they are gripped.

5. In handle construction for braces and the like, in combination, a hollow member having its end edges inclined outwardly with respect to its axis, and a pair of end members having similarly inclined annular recesses formed therein, the walls of which are forced into interlocking relation with said edge portions of said hollow member.

6. In handle construction for braces and the like, in combination, a hollow member having a convex body portion and outwardly flared ends, and a pair of end collars provided with grooves into which said flared ends rest and with which they interlock.

7. In handle construction for braces and the like, in combination, a hollow member having a convex body portion and outwardly flared ends, and a pair of end collars provided with grooves into which said flared ends rest and with which they interlock, said hollow member being built up of a plurality of longitudinal sections.

8. In handle construction for braces and the like, in combination, a handle member having bearings at its ends upon the crank portion of the brace, and a pair of parts secured to and outwardly projecting from the surface of said crank, one adjacent each end of said handle member and adapted to engage the inner surface of said handle and prevent longitudinal movement thereof.

9. In handle construction for braces and the like, in combination, a hollow handle built up of a plurality of longitudinal sections formed of sheet metal and each provided with an inclined edge portion, a pair of end collars having similarly inclined annular recesses formed therein adapted to receive and grip said edge portions and support said hollow member rotatably upon the crank portion of the brace, and a pair of parts projecting from the surface of said crank portion adapted to engage the inner surfaces of said collars and limit the longitudinal movement of the handle.

10. In handle construction for braces and the like, in combination, a hollow handle member having outwardly flared end portions, a pair of collars one at each end of said hollow handle member each having a portion journaled upon the brace and a portion spaced from said first portion, said two spaced portions forming a recess inclined similarly to the flared ends of said handle member and in which said ends are gripped.

In testimony whereof, I have signed my name to this specification this eighth day of April, 1921.

WALTER I. TUTTLE.
